UNITED STATES PATENT OFFICE.

JACOB V. MOTTER, OF CINCINNATI, OHIO.

INJECTOR.

SPECIFICATION forming part of Letters Patent No. 557,081, dated March 24, 1896.

Application filed November 4, 1895. Serial No. 567,812. (Model.)

To all whom it may concern:

Be it known that I, JACOB V. MOTTER, a citizen of the United States, residing at Cincinnati, in the county of Hamilton and State of Ohio, have invented certain new and useful Improvements in Injectors, of which the following is a full, clear, and exact description, reference being had to the accompanying drawings, forming part of this specification.

10 My invention relates to that class of automatic steam-injectors for charging boilers with water, and primarily designed for locomotive-boilers, though capable of use wherever injectors are required. Its object is to improve both the construction of the parts, whereby lightness, simplicity and compactness are obtained, and to render the action of the injector more sure and perfect at all times.

15 The novelty of my invention will be hereinafter set forth, and specifically pointed out in the claims.

In the accompanying drawings, Figure 1, Sheet 1, is a side elevation, partly in section, of so much of an injector as is necessary to 20 illustrate my invention. Fig. 2, Sheet 2, is a transverse section through the dotted line $x x$ of Fig. 1.

The same letters of reference are used to indicate identical parts in both figures.

25 Except as hereinafter pointed out, the injector is of a well-known type, and in describing it generally it is only necessary to say that A is the exterior shell, with diaphragms B, C, D, E and F, forming the chambers G, H, I, J, K, and L, of which G is the water-inlet controlled by the usual valve, (not shown,) which seats in the diaphragm B.

30 H is the steam-inlet chamber, having projecting through diaphragm C the steam-40 projecting tube M, controlled by ram-valve N of the usual or any suitable construction.

I is the water-lifting chamber, with water-lifting tube O in line with tube M in the usual manner and projecting through diaphragm 45 D into chamber J.

P is the combining-tube in line with tubes O and M and projecting through diaphragm E and F, and Q is the water-tube leading to boiler and provided with the usual check-valve. The diaphragm is perforated, as shown by dotted lines at a, to establish communication between chambers L and K, and serves

no other purpose than to support tube P at its discharge end, said chamber L being practically part of chamber K. Directly over the 55 chamber K is a discharging-chamber formed of a bonnet R, into which is screwed a plug-cap T, from which bonnet-chamber a passage r, Fig. 2, extends on either or both sides of chamber K to the overflow-discharge S. An 60 L-shaped tube j extends centrally up into the bottom of chamber R, and its opposite flattened and enlarged end opens into chamber J through diaphragm E. A port b is left between the tube j and the ledges or seats c at 65 the bottom of chamber R. A winged valve d, provided with wings d', Fig. 2, fits and is guided in the chamber R and is seated partly on the upper end of tube j and on the ledges c, and within its hollow and counterbored 70 stem is a second independent valve e, which is guided in valve d and is seated entirely upon the upper end of the tube j. A frost-valve stem t, Fig. 2, has a threaded bearing through the plug T and is located over the 75 valve d and can be brought into action to hold both valves seated in locomotive service when desired.

The operation of the injector, under the foregoing description, is as follows: Should 80 the break occur in the chamber J, the exhaust would raise the valve e, which latter would carry with it valve d to give relief to both chambers simultaneously until the jet having been again established with a sufficiency 85 of water to properly actuate the injector the valve e would first be drawn to its seat by the vacuum produced in the overflow-chamber J, and then the valve d, after remaining open sufficiently to relieve chamber K, would 90 be closed. Should the break occur, however, at the discharge end of the tube P, only the valve d would be raised to relieve the overflow and the valve e would remain seated to prevent any churning back from the chamber 95 K to the chamber J through the tube j, and thus the jet would be more quickly established, as will be readily understood.

By this construction the injector is not only simplified in its construction and rendered 100 lighter and more compact, but its action is rendered entirely automatic and quick to relieve breaks and restore the jet. Furthermore, the automatic valve e is elevated and

can never be submerged in water, which invariably causes incrustation and prevents the action of the same at any and all times in the usual automatic type of injectors where 5 said automatic valves are submerged.

Having thus fully described my invention, I claim—

1. In an injector, the combination of adjacent overflow-chambers provided with adjacent escape-openings, a single discharge-chamber into which said openings enter, and two valves having seats on one plane in said chamber for said openings, the inner one carrying the outer one when opened and the outer

one being independent in its action from the 15 inner one substantially as described.

2. In an injector the combination of the adjacent chambers J and K, the chamber R above the chamber K, the L-shaped tube *j*, entering chamber R from chamber J the port 20 *b*, from chamber K to chamber R and the valves *d* and *e* having seats on one plane for the port *b* and tube *j* respectively, substantially as described.

JACOB V. MOTTER.
